DESIGN FOR A DRESS ENSEMBLE

Montrose Fox Egbert, New York, N. Y.

Application January 24, 1942, Serial No. 105,401

Term of patent 3½ years

To all whom it may concern:

Be it known that I, Montrose Fox Egbert, a citizen of the United States of America, residing in New York city, county of New York, and State of New York, have invented a new, original, and ornamental Design for a Dress Ensemble, of which the following is a specification, reference being had to the accompanying drawing, forming part thereof, wherein,

I claim:

The ornamental design for a dress ensemble, substantially as shown.

MONTROSE FOX EGBERT.
